UNITED STATES PATENT OFFICE.

FRANK J. JARECKI, OF GRAND RAPIDS, MICHIGAN.

TUBE-FORMING MACHINE.

1,288,603.

Specification of Letters Patent. Patented Dec. 24, 1918.

Application filed June 12, 1916. Serial No. 103,201.

To all whom it may concern:

Be it known that I, FRANK J. JARECKI, a citizen of the United States of America, residing at Grand Rapids, in the county of

5 Kent and State of Michigan, have invented certain new and useful Improvements in Tube-Forming Machines, and I do hereby declare the following to be a full, clear, and exact description of the invention, such as 10 will enable others skilled in the art to which it appertains to make and use the same.

This invention relates to a metal forming machine it being a primary object and purpose of the invention to produce a machine 15 in which strips of flat metal may be formed into tubes and a joint made at the edges of the metal which is absolutely locked against separation and at the same time formed so that the finished tube presents on its outside 20 a smooth surface without any ridge to indicate the position of the joint or seam, the machine also being adapted to make many other forms. A further object of the invention consists in the provision of means for 25 withdrawing the tube or other structure from the machine this withdrawing means rendering it possible to make tubes or the like of any length and not requiring long strips of metal for operation of the machine. 30 Still further objects of the invention consist in the provision of novel mechanism for making the locking seam, novel construction to permit the adjustment of the seam forming rollers for different thicknesses of metal, and in various other novel 35 features of construction and arrangement of parts all of which will fully appear in the following description, reference being had to the accompanying drawings, in which:

40 Figure 1 is a side elevation of the complete machine.

Fig. 2 is a similar elevation from the opposite side of the machine.

Fig. 3 is a plan view thereof, certain parts 45 being broken away and shown in section.

Fig. 4 is a fragmentary plan view showing a set of rollers and forming members for forming metal strips into another shape.

Fig. 5 is a plan view of the arbor or mandrel around which the tube is formed.

Fig. 6 shows a side elevation and end view of the form produced by the mechanism shown in Fig. 4.

Fig. 7 is a view similar to Fig. 6 of the 55 tube which is formed by the mechanism shown in 1-3 inclusive.

Fig. 8 is an end elevation of the arbor or mandrel.

Fig. 9 is a plan view, enlarged, of the seam forming mechanism. 60

Fig. 10 is an end elevation thereof.

Fig. 11 is a vertical section taken longitudinally of the device shown in Fig. 9 looking against the inner rolls thereof.

Fig. 12 is a similar section looking in the 65 opposite direction or against the outer rolls.

Fig. 13 is a vertical transverse section, enlarged, through the rear part of the seam forming mechanism.

Fig. 14 is an enlarged elevation of the 70 finishing elements of the mechanism shown in Fig. 4.

Figs. 15, 16, and 17 are elevations of the consecutive bending and forming rolls which act upon the metal strip to bend it 75 into tubular form before it reaches the seam forming mechanism.

Fig. 18 is a vertical transverse section through the member which supports the arbor or mandrel. 80

Fig. 19 is a front end elevation of the seam forming mechanism showing the action of said mechanism in aiding in forming a tube.

Figs. 20, 21, and 22 are views showing 85 consecutive steps in the progress of forming the seams.

Fig. 23 is an elevation from the front end of the withdrawing mechanism the supporting bar therefor being shown in section. 90

Fig. 24 is a plan view of a detail of a part of the withdrawing mechanism.

Figs. 25 and 26 are, respectively, a plan and front elevation of a modification in the structure of the seam forming device. 95

Fig. 27 is an end view looking at the front thereof.

Figs. 28, 29, 30, 31, 32, 33 and 34 are transverse sections taken through the device shown in Figs. 25 and 26 and illustrating 100 consecutive steps of the formation of the seam, and

Fig. 35 is a transverse section taken through the mandrel at the position of the last rollers mounted in said mandrel. 105

Like reference characters refer to like parts throughout the several views of the drawings.

A bed 1, preferably of cast iron, is used on which to mount the various forming rollers, and seam forming device it being supported by end posts 2. A shaft 3 is mounted 110

in bearings and extends transversely under the bed 1, a wheel 4 being fixed on the rear end of the shaft. A belt 5 adapted to be driven by any suitable engine, motor or other source of power passes around wheel 4. A pinion 6 is fastened to shaft 3 closely adjacent wheel 4 and meshes with a gear 7 fixed to the rear end of a shaft 8 which extends through the bed 1. A gear 9 of less size than gear 7 is fixed to shaft 8 immediately back of the bed, it in turn having engagement with a gear 10 of the same size as gear 9 directly above it which is mounted on a shaft 11 this shaft also extending through the bed 1. Gear 9 also engages with idle pinions 12 and 13 one at either side of the gear as shown in Fig. 2, such pinions meshing with gears 14 and 15 mounted on the rear ends of shafts 16 and 17 of the same size as gears 9 and 10. Directly above and engaging with gears 14 and 15, respectively, are gears 18 and 19 fixed on the rear ends of shafts 20 and 21. Shafts 16, 17, 20 and 21 extend through to the front side of the bed 1 and shafts 20, 11 and 21 lie in the same horizontal plane and directly above shafts 16, 8, and 17 respectively, which also lie in the same horizontal plane. The gear 15 drives an idle gear 22 as shown in Fig. 2 which in turn engages with a gear 23 mounted on the rear end of a shaft 24 in the same horizontal plane with shafts 16, 8, and 17. Gear 23 engages with and drives a gear 25 directly above which is fixed on the rear end of a shaft 26, this shaft lying in the same plane with shafts 20, 11, and 21. Shafts 24 and 25 also extend to the front of the bed and the gears 23 and 25 thereon are of the same sizes as the gears on shafts 16, 20, 11, 8, 21 and 17 so that each of these shafts extending through the bed is driven at the same rate of speed. The upper shafts are mounted in suitable adjustable bearings 27.

On the forward ends of shafts 16 and 20 are mounted rolls 28 and 29 one below the other, the former of which at its rear is provided with a flange 30 having an inclined face as shown in Fig. 15 which is formed as a complement of the beveled part 31 at the rear of the upper roll 29. Similarly the upper roll 29 has a flange 32 with a rear inclined face formed as a complement to the beveled front portion 33 of the lower roller 28. The second pair of shafts 8 and 11 on their front ends carry lower and upper rollers 34 and 35, the former of which has a concave surface and the latter a convex surface adapted to fit in said concave surface of roll 34. The next pair of shafts 17 and 21 also carry rolls 36 and 37. The former is of considerable width and formed with a concave surface while the latter is much narrower and has a convex surface as best illustrated in Fig. 17. A feeding table 38 is supported at the forward side and end of the bed and

has spaced apart guides 39 between which the metal strip 40 which is to be formed into a tube is fed to the machine, it entering first between rollers 28 and 29 passing therefrom to rollers 34 and 35 and thence to rollers 36 and 37. The first pair of rollers form lips 41 and 42, as shown in Fig. 15, at opposite edges of the strip and turned at an angle in opposite directions. The other rollers serve to bend the metal lengthwise and by successive steps the metal strip approaches the form of a tube. Between the first pair of rollers 28 and 29 and the second pair 34 and 35 suitable guides 43 carried by brackets 44 adjustably mounted on the front of the bed 1 are provided to pass the strip properly from one pair of rollers to the other and, similarly, between the second pair of rollers 34 and 35 and the third pair of rollers 36 and 37, guides 45 and 46 carried by brackets 47 which are also adjustably mounted on the front face of the bed 1, are also provided for the same purpose.

The metal as it passes from rollers 36 and 37 enters between plates 48 and 49 spaced apart and carried on a lower plate 50 secured in any suitable manner to the front of bed 1. These plates incline toward each other from their front to their rear ends and as the metal strip passes by them its edges are brought more and more closely together. The plate 48 at its inner side is properly formed to receive the lip 42 bent at one edge of the metal strip as shown in Fig. 18. A mandrel or arbor 51 substantially cylindrical in form lies between plates 48 and 49 and is partially received in a concave depression formed in the plate 50 this mandrel being of such a size in respect to the depression that the metal strip may pass between it, plate 50 and plates 48 and 49, it being in this manner formed at its under side as a cylinder. At its front end and on its upper side, the mandrel has an integral member 52 tapering gradually toward the rear and coming to a point, the taper being the same as the inclination of parts 48 and 49 toward each other whereby the edges of the metal strip are forced as they pass between said members 48 and 49 to approach each other. The mandrel is supported at its front end by a block 53 attached to a bracket 54 secured to the bed 1. The metal strip now substantially in the form of a tube, passes from parts 48 and 49 to the seam forming mechanism device which is supported on a bracket 55 secured to the front face of bed 1. Two bars 56 and 56^a, one located in front of the other, lie upon the bracket and are connected thereto. At the front ends of the blocks rollers 57 and 58 are mounted on vertical spindles, the former a little ahead of the latter, both rollers having concave surfaces the curvature of which is the same as that of the

tube to be formed while the roller 57 has an upper flange 59 over which the lip 42 is guided as shown in Fig. 19. The opposite edge and lip 41 of the metal strip 40 is forced over lip 42 by the upper flange of roller 58. Directly back of roller 57 and mounted on the forward bar 56 is a roller 60 positioned on an incline as shown and located so as to force the lip 41 against lip 42 as the metal passes by it passing therefrom to a roller 62 directly back of roller 60 which has a flange 63 so formed and shaped as to turn the lip 41 to overlap lip 42 as illustrated in Fig. 20, there being a block 61 secured directly opposite this roller for the metal of the tube directly opposite the flange 63 to bear against. Back of roller 62 is a roller 64 mounted on a vertical axis and having at its under side a flange 64^a. Coöperating with said roller is a roller 65 mounted on the opposite bar 56^a at an angle more nearly approaching the vertical than roller 62, and acting with the flange 64^a to turn the seam farther over as shown in Fig. 21. Positioned along the length of the mandrel on its upper side are a number of bearing rollers 66 with convex surfaces which come directly underneath the seam forming rollers in this manner eliminating considerable friction which would otherwise be present. Back of the rollers 66 in the mandrel is another roller 67 of substantially the same diameter but having a concave groove 68 therein into which the seam formed by the interlocking of lips 41 and 42 is pressed by a roller 69 mounted on a block on a horizontal axis, directly above roller 67. The seam in this manner is pressed down below the outer surface of the tube so that the completed tube presents a smooth outer surface. In Fig. 13 I have shown the roller 69 mounted on the bearing 70 carried eccentrically on a pin 71 this roller 69 as well as the various other rollers described being thus mounted to provide an easy adjustment of the rollers toward or from each other for different thicknesses of metal the pins such as illustrated at 71 being held in adjusted position by set screws such as shown. Furthermore for easy passage of the tube of metal between the bars 56 and 56^a I have mounted rollers 72 formed with concave surfaces to fit the under side of the tube and such rollers may also be adjusted in the same manner by means of the same eccentric mount. The tube as it passes from the seam forming device follows the mandrel which is provided with a groove 68^a between the front and rear rollers 67 to pass the seam which has been pressed down below the outer surface of the tube and finally passes between the lower and upper rollers 24^a and 26^a secured on the front ends of the shafts 24 and 26. These rollers have concave grooves formed in their surfaces to fit the tube that passes between them and the upper roller bearing against the lock seam forces it farther into the groove 68 of the roller 67 which is mounted at the end of the mandrel 51. The tube as it leaves these rollers is absolutely smooth without any ridge to indicate the presence of a joint or seam in the tube.

Strips of metal passed through the machine and formed into tubes as described will continue to pass as long as there is left an end to be engaged by the rollers 36 and 37, but after the end of the strip is passed beyond these rollers the pull on the tube made by rollers 24^a and 26^a is not sufficient to draw the tube entirely from the machine. To provide for the withdrawal of a tube from the tube forming mechanism and to make a machine workable for making tubes of any length, long or short, I have provided a device which is operable to engage with a portion of the tube passed beyond rollers 24^a and 26^a to grasp it and pull the unfinished portion from the machine.

The support for this device comprises a horizontal T-bar 73 attached at its front end to the bed 1 and supported at its rear end by an upright 74. Slidably mounted on the bar are upper and lower bars 75 and 76 which are fastened together so as to move in unison by a plate 77. The bar 75 in its under side is formed with a concave groove 78 semi-circular in cross section and of a diameter slightly less than the outside diameter of the tube formed by the machine. Below groove 78 a similar groove 79 is formed in a bar 80 which lies upon and is supported by the sleeves 81 pivotally mounted upon studs 82 and 83 projecting outwardly from the bar 76. Sleeves 81 are formed with cam projections so that on rotation thereof the bar 80 is elevated and brought closer to the bar 75 in this manner grasping any tube that has been entered into the opening made by the grooves 78 and 79. A lever 84 is preferably formed integral with the forward sleeve and extends upwardly as shown in Fig. 1, a bar 85 being pivotally connected thereto a distance below its upper end, extending to the rear and having pivotal connection with the upper end of another lever 86 formed integral with the other sleeve 81 mounted on pin 83. At its upper end lever 84 has pivotal connection with a sleeve 87 slidably mounted upon a rod 88 which is mounted lengthwise of the machine for slidable movement in supports 89 and 90, the latter being positioned at the front of the bed 1. Sleeve 87 normally is in contact with a collar 91 adjustably mounted upon rod 88 and a coil spring 92 surrounds the rod 88 between the collar 91 and support 89 being secured at its ends to said members the tendency of which is to hold rod 88 in its normal position shown in Fig. 1. At its rear end rod 88 has a stop

collar 93 adjustably mounted thereon and at either side of the forward support 90 stop collars 94 are also adjustably mounted upon the rod.

5 A member 95 is slidably mounted in the upper side of bar 75 at its rear end having an upright projection 95^a to which the rear end of a bar 96 is pivotally connected, said bar at its forward end being pivotally connected to the lever 84 heretofore described. Member 95 is provided with a diagonal slot 97 in which a pin carried at the end of a lever 98 seats, said lever being secured to the upper end of a vertical shaft 99 pivotally mounted in a suitable bearing on the plate 77. A lever 100 is fastened to the lower end of shaft 99 and a short distance to the front connects with a collar 101 formed with a clutch face 102 and splined on the stud shaft 103 which is carried by the plate 77 previously described, projecting to the rear therefrom. A sprocket wheel 104 is loosely mounted on this shaft it also being provided with a clutch face 105 adapted for engagement with the clutch face 102 but normally disengaged therefrom.

Meshing with gear 23 is an idle pinion 106 which drives gear 107 secured to the end of a shaft 108, this shaft being mounted in suitable bearings secured to the rear end of the bed 1. A sprocket wheel 109 is secured to the forward end of this shaft and an endless sprocket chain 110 passes around sprocket wheel 109 and also around a sprocket wheel 111 mounted upon the upright support 74. The upper run of the sprocket chain 110 passes over and engages with the teeth of sprocket wheel 104, it being evident that when the machine is in operation sprocket chain 110 is in continuous movement and that the sprocket wheel 104 turns continuously. A block 112 projects upwardly from the member 75, as shown in Fig. 1 and to this block the end of a chain 113 is secured, it passing around a sprocket wheel 114 rotatably mounted on the bed 1, thence to the rear and over the idle sprocket wheel 115 rotatably mounted on the upper end of upright 74 and thence down and around a sprocket wheel 116 rotatably mounted upon a short shaft 117 which is carried by ears 118 projecting upwardly from a weight 119, the chain finally terminating at the bar 73 as shown in Fig. 1 and being secured to this bar. Below the weight 119 any preferred type of stop or bumper 120 may be placed.

In operation after a length of tubing has been formed and extended into the grooves at 78 and 79 between bars 75 and 80, and 60 the metal from which the tube is formed has passed beyond rollers 36 and 37, the operator grasps the handle on the forward end of the rod 88 and pushes the rod until stop 94 contacts with support 90. As this 65 operation takes place the turning of cam

sleeves 81 elevates bar 80 so that the tube is grasped between said bar and the upper bar 75. At the same time bar 95 is moved to the rear causing the rotation of lever 98 and of shaft 99 connected thereto, by reason 70- of the diagonal formation of slot 97 in the bar 95. The rotation of the shaft 99 throws lever 100 and collar 101 toward the sprocket wheel 104, clutch members 102 and 103 therefrom engaging with each other. As sprocket 75 wheel 104 is continuously rotating the effect of this engagement is to cause the entire device to move along the supporting T-bar 73 toward the upright 74 it being apparent that, as this movement takes place, the end 80 of the material still remaining in the tube forming portion of the machine is withdrawn therefrom. The movement of the device along bar 73 continues until sleeve 87 strikes against stop collar 93 whereupon 85 lever 84 and the members associated therewith are carried to their normal position, shown in Fig. 1, and clutch members 102 and 103 are disengaged. Weight 119, elevated 90 during this operation returns the device to its normal position against the rear end of bed 1 whereupon the operation may be repeated when desired.

The machine is also adapted to turn other forms than the tube described. In Fig. 4 95 there is shown a series of rolls for forming a different form from that heretofore described. A strip of metal passes between the upper and lower rolls 121 and 122 going thence to the second pair of rolls 123 and 124 being shaped by such rolls into a channel. The channel is carried to a third pair of rolls comprising an upper roll 125 having a central annular rib 127 which engages with a lower roll 128 whereby the metal is made 100 to approach the form shown in Fig. 6, the edges of the metal strip being turned upwardly as indicated at 129 while the central portion of the strip is formed with outward bends 130. To complete this form the metal 105 passes from the last pair of rolls being guided by members 131 having downwardly turned fingers 132 which enter between the upturned edges 129 previously described. Members 131 are fastened in spaced apart 110 relation to a supporting block 133 which is secured to the front face of the bed 1; and near the rear end of the supporting block a pair of forming rolls 134 best shown in Fig. 14 are mounted at an angle to the vertical 115 and engage against each side of the metal to complete its form. As thus formed it passes under the roller 135 having a central annular rib 136 which enters between the upstanding edges 129 and below the roller 135 a companion roller formed to engage the under side of the metal as it passes from the machine, may be positioned. The device for pulling tubes from the machine may be used 125 with this form quite as well, the only altera- 130

tion necessary being to provide grooves in bars 75 and 80 of a shape to fit the particular form of metal structure made by the machine.

- 5 A modification in the seam forming mechanism is shown in Figs. 25 to 35 inclusive. In this structure a bar 137 is secured to the front face of the bed back of the rollers 36 and 37. Secured to and in front of bar 137 is a bar 138. A bracket 139 is suitably supported at the front ends and above said bars to which the front end of a cylindrical mandrel 140 is fastened by the screw 141, said mandrel extending to the 10 rear and passing between bars 137 and 138 which are formed to permit this passage and leave a space so that the metal of which the tube is formed may pass between the mandrel and said bars. This mandrel on its 15 upper side has a rearwardly tapering element 142 serving the same purpose as the part 52 on mandrel 51 in the previously described construction. The metal strip passing under this device around the mandrel 20 comes first to a concave roller 143 located below the mandrel and between bars 137 and 138 there being mounted in the under side of the mandrel a small roller 144. It now passes to two rollers 145 and 146 set on an 25 incline and serving to first engage the two lips 41 and 42 at the edges of the strip 40 and directly below these rollers is positioned 30 a horizontal roller 147 set in the upper side of the mandrel. The metal is next engaged by rollers 148 and 149 of the formation 35 shown in Fig. 30 which are set oppositely on the two bars 137 and 138 and at different angles to the vertical, serving to further engage and bend lips 41 and 42 to make 40 the seam. The seam is then further formed by oppositely disposed rollers 150, 151, 152, and 153 there being a progressive forming of the 45 seam to more closely approach the finished product as it is acted upon by the successive 50 rollers; and it will be observed, under all of these rollers there is mounted one of the small anti-friction rollers 147 previously described, each of said rollers having a convex surface the radius of curvature of which is 55 identical with the curvature of the mandrel. As the seam passes from rollers 152 and 153 it is practically formed except for crushing it down below the outer surface of the tube. This is effected by two rollers 154 mounted 60 on bar 137 as shown in Fig. 33 each having a concave surface which comes directly above a similar surface in a small roller 155 mounted in the mandrel. It is apparent that the seam is forced into the concavity of the 65 rollers 155 mounted below rollers 154. The tube practically complete leaves the seam forming device to be engaged by the rollers 26^a and 24^a which are mounted above and below the small rollers 156 and 157 located 70 near the end of the mandrel and within the 75 body thereof, it being apparent that the upper roller 156 must have a concave surface and that the end of the mandrel must be grooved as shown at 158 for the portion of its rear length to permit the passage of the 70 seam in the tube.
- The foregoing construction of lock seam forming mechanism is a preferred construction as with it the seam may be formed perfectly to the extreme end of the tube while 80 in that shown in Figs. 9 to 22 inclusive about one inch in the last end of the tube is not perfectly formed. The method of forming the seam is practically identical in both constructions though there is in the last construction greater freedom from friction in the provision of the plurality of rollers 147 and also the plurality of rollers 143 and 144 associated with the mandrel which aid the 85 passage of the metal thereover and eliminate friction as far as it is possible.
- I claim:
1. In a device of the character described, means for bending a strip of metal into tubular form, means for interlocking the 90 side edges of said strip to make a seam extending the length of the tube, means for driving said tube forming means, means for grasping a tube and withdrawing it from the seam forming means, said withdrawing 95 means being normally disconnected from the driving means, and operator-controlled means for connecting said withdrawing means with the driving means.
  2. In a device of the character described, 100 means for bending a strip of metal into tubular form, means for interlocking the side edges of said strip to make a seam extending the length of the tube, means for driving said tube-forming means, means for grasping a tube and withdrawing it from the seam-forming means, said withdrawing 105 means being normally disconnected from the driving means, operator-controlled means for connecting said withdrawing means with the driving means, and means for automatically disconnecting the driving means from said withdrawing means on completion of a 110 predetermined movement of said means.
  3. In combination, a support, means 115 mounted on the support adapted to bend a strip of metal into tubular form, means to drive said tube forming means, means on the support adapted to interlock the side edges of said tube and make a longitudinal 120 seam therein, a bar extending from the rear end of the support, a device slidably mounted thereon into which a tube is adapted to enter, operator-controlled elements in said device adapted to grasp the tube, and means 125 rendered effective simultaneously with the grasping of the tube for connecting said device with the driving means to move the device along the bar away from the support, substantially as described. 130

4. In combination, a support, means for forming a strip of metal into a tube mounted on the support, a driving means, a bar extending to the rear from the support, a device slidably mounted on the bar into which the tube is entered, means on said device comprising a relatively stationary bar and a bar movable toward said stationary bar to grasp the tube, means to move said movable bar toward the stationary bar, and means operated simultaneously therewith to connect the device to the driving means to move it along said first mentioned bar away from the support.
5. In combination, a support, means on the support for continuously forming a flat metal strip fed to said means into a tube, a device mounted at the rear end of the support for movement away from and toward the support, means carried by said device to grasp a tube entered into it, a driving means for the tube-forming means, manually operable means for connecting said device with the driving means to move it away from the support and simultaneously causing the grasping means to engage with the tube, means automatically disconnecting the driving means from the device after it has moved a predetermined distance from the support, and simultaneously releasing the grasping means, and means to return the device to normal position adjacent the support on disconnection thereof from the driving means.
6. In combination, a support, means on the support for continuously forming a flat metal strip fed to said means into a tube, a bar extending rearwardly from the support, a device slidably mounted on the bar into which tubes formed by said means enter, a driving means for the tube-forming means, means on said device for grasping a tube entered into it, means for operating the tube-grasping means and simultaneously connecting said device with the driving means to thereby move it along the bar away from the support, means automatically disconnecting the driving means and releasing the grasping means on completion of a predetermined movement of the device away from the support, and a weight connected to the device and elevated thereby as it moves away from the support, said weight returning the device in normal position on disconnection thereof from the driving means.
7. In combination a supporting bed, means thereon for forming a metal strip into a tube, a bar extending rearwardly from the bed, an upright supporting the rear end of the bar, a device slidably mounted on the bar, a shaft on the bed, a sprocket wheel on the shaft, an idle sprocket wheel on the upright, a sprocket wheel mounted to turn on said device, an endless sprocket chain passing around the first two wheels and engaging with the last mentioned wheel, means to drive the shaft, means on said device to grasp a tube entered therein, and means to cause said means to grasp a tube and simultaneously lock the last mentioned sprocket wheel against movement with respect to said device.
8. In combination, a supporting bed, means thereon for forming a metal strip into a tube, a bar extending rearwardly from the bed, an upright supporting the rear end of the bar, a device slidably mounted on the bar, a shaft on the bed, a sprocket wheel on the shaft, an idle sprocket wheel in the upright, an endless chain around said sprocket wheels, means to drive the shaft, a sprocket wheel mounted to turn on said device with which one rim of the chain engages, means on said device for grasping a tube entered into it from the tube forming means, means to render said grasping means effective and simultaneously lock the sprocket wheel carried by the device to said device, means automatically releasing said sprocket wheel and the grasping means after said device has moved a distance away from the bed, and means to return said device to initial position after such release.
9. In combination, a supporting bed, a bar projecting rearwardly therefrom, means to support the outer end of the bar, upper and lower bars slidably mounted on said bar, a plate connecting said upper and lower bars together, cam sleeves rotatively mounted below said upper bar, a bar laid loosely on said sleeves below said upper bars, said upper bar and last mentioned bar having grooves cut therein to receive a tube, a shaft projecting from the plate and fixed thereto, a sprocket wheel loosely mounted on the shaft, means to continuously drive the sprocket wheel, a clutch member splined in the shaft adapted to connect with the sprocket wheel and means to simultaneously rotate the cam sleeves to elevate said last mentioned bar and connect the clutch member with said sprocket wheel.
10. In combination, a supporting bed, means thereon to form a flat metal strip into a tube and join the meeting edges together, a supporting bar extending rearwardly from the bed, upper and lower bars slidably mounted on said first bar, a plate connecting said upper and lower bars, front and rear pins projecting from the lower bar, cam sleeves rotatably mounted on the pins, front and rear levers secured to the sleeves and extending upwardly, a member connecting the levers, a bar laid loosely on the sleeves said upper bar and last mentioned bar having adjoining grooves to receive a tube, a member having a diagonal slot and slidably mounted to move lengthwise of the upper bar, a rod connecting the front lever and said member, an operating rod slidably

mounted above and lengthwise of the bed, a sleeve loosely mounted on said operating rod, a pivotal connection between the sleeve and the upper end of the front lever, stop 5 collars on the operating rod at either side of the sleeve, a vertical bearing on the plate, a vertical shaft rotatively mounted therein, an upper lever fixed to said shaft and having means at its end entering said diagonal 10 slot, a lever secured to the lower end of the vertical shaft, a shaft projecting from the plate, a clutch member splined thereon, con-

nctions between the clutch member and said last mentioned lever, a sprocket wheel loosely mounted on said last mentioned shaft, an endless sprocket chain lying lengthwise of the supporting bar having one rim engaging with the sprocket wheel, means to drive said chain, and a clutch member in the sprocket wheel adapted to be engaged by 15 said first clutch member on operation of the operating rod, substantially as described.

In testimony whereof I affix my signature:

FRANK J. JARECKI.
